UNITED STATES PATENT OFFICE.

EDISON E. RANDALL, OF KANKAKEE, ILLINOIS, ASSIGNOR TO PARAMOUNT KNITTING COMPANY, OF CHICAGO, ILLINOIS, A CORPORATION OF ILLINOIS.

KNITTING-MACHINE.

1,210,837.

Specification of Letters Patent.

Patented Jan. 2, 1917.

Application filed October 28, 1913. Serial No. 797,885.

To all whom it may concern:

Be it known that I, EDISON E. RANDALL, a citizen of the United States, residing at Kankakee, county of Kankakee, State of Illinois, have invented an Improvement in Knitting-Machines, of which the following description, in connection with the accompanying drawing, is a specification, like characters on the drawing representing like

10 parts.

This invention relates to knitting machines and is concerned with means for measuring the length of the knitted web and for controlling the change from one kind of 15 knitting to another upon the completion of a predetermined measured length of the web.

In the knitting of a web of material such, for example, as a stocking, it is found in practice that it is very difficult to obtain the 20 same length of web in a plurality of articles knitted although the number of courses of knitting may be precisely the same. This is due to the varying quality of yarn, to the varying tension and to various other causes 25 which it is practically impossible to overcome. It is important in knitted articles, especially those that are to be used for wearing apparel, such as a stocking, that the dimensions of the parts of the article shall be 30 accurate. Such articles as stockings, for example, vary or differ in linear measurement between the various sizes to a comparatively small extent. In stockings it is important that the length of the foot and the length of 35 the leg should be exact and the same in all stockings of a given size.

This invention provides two mechanisms for measuring the web, one of which measures by the number of courses knit and the 40 other of which measures the actual length of the web. It further provides means by which either of these measuring means may be brought into action as desired. It further provides for the change from one kind 45 of knitting to another upon the completion of a predetermined length of web as determined by either of the measuring means in action. In the knitting of a stocking, for example, where the knitting proceeds beginning at the toe, reciprocating knitting may 50 be employed for knitting the toe pouch and upon the completion of a predetermined number of courses a change will automatically be effected to plain circular knitting

which will continue until the heel pouch is 55 to be begun. The length of this plain circular foot portion will determine the length of the foot. This foot portion may be measured either by the number of courses knit or by the employment of the means for determining the actual length of the foot portion. When the prescribed number of courses have been knit or when the prescribed length has been knit then a change will automatically 60 be effected to the reciprocating knitting for 65 the heel pouch. Upon the completion of a predetermined number of courses of reciprocating knitting a change will then be effected usually to plain circular knitting for the ankle portion. The length of the ankle 70 portion may be measured by the number of courses knit or by the actual length of the web as either mechanism is used. Upon the completion of the prescribed length as determined by either mechanism, a change is 75 automatically effected to ribbed knitting or if the stocking is not to have a ribbed leg, plain circular knitting, beginning at the termination of the heel pouch will continue through the length of the leg. While it may 80 be desirable to measure the actual length of the foot portion accurately, it is in the knitting of the leg portion that the greatest variation takes place and while this portion is 85 being knit the measuring means which determines the actual length of the web rather than the number of courses knit is employed whether the leg be knit of plain circular work or of ribbed work.

The nature of the invention will more 90 fully appear from the accompanying description and drawings and will be particularly pointed out in the claims.

The drawings illustrate so much of a knitting machine arranged for knitting ribbed, 95 plain circular and reciprocating work as is necessary to an understanding of the present invention. A knitting machine is a complicated machine and as the present invention is concerned only with the measuring of the 100 web and the control of the change from one kind of knitting to another, those parts of the machine not directly involved have been omitted for the sake of clearness.

In the drawings: Figure 1 is a view in 105 front elevation of a knitting machine showing only those parts necessary to an understanding of the invention. Fig. 2 is a de-

tail of the mechanism for operating the main ratchet for the pattern shaft, partially in cross section and looking toward the right of the machine. Fig. 3 is a side elevation looking at the right hand side of the machine shown in Fig. 1. Fig. 4 is a detail of some of the mechanism for throwing into and out of operation the device for measuring the actual length of the web, being a cross section taken on the line *a—a* of Fig. 5. Fig. 5 is a rear elevation of the device shown in Fig. 4. Fig. 6 is a detail showing the ratchet wheel clutch controlling disk and operating pawl. Fig. 7 is a detail of a drum and its operating pawl forming a part of the mechanism.

The knitting machine illustrated in the drawings is particularly adapted for the knitting of ribbed leg stockings and contains provision, therefore, for the knitting of plain circular, reciprocating and ribbed work but as the details of such machines are well known and familiar to those skilled in the art and are not involved with the present invention, they are not illustrated.

The frame of the machine is shown as comprising the vertical standards 1, 2, 3 and the top plate 4. The main shaft is indicated at 5 provided with the fast and loose pulleys 6 and 7 by which power is transmitted to the machine. The usual cylinder needles are mounted in the cylinder 8 and the usual dial needles in the dial plate 9. The usual cam for the cylinder needles is driven by the bevel gear 10 and the cam 11 for the dial needles when locked by the pin 12 actuates the dial needles. When the dial cam is unlocked by the pin 12 the dial needles are out of action. A lever 13 is controlled by a star wheel 14 to move the pin and lock or unlock the cam for the dial needles when required and the operation of this star wheel is secured by a riser 15 being brought into its path. These elements may be all as more fully described and illustrated in the patent to Huse and Huse, Reissue No. 12,917 granted February 9, 1909. The movement of the riser 15 is controlled by suitable pattern mechanism and determines the change from plain to ribbed knitting and vice versa.

The change from plain circular to reciprocating work may be effected in any suitable and well-known manner and one well-known form of mechanism is sufficiently illustrated as an example. The bevel gear 150 which drives the bevel gear 10 is rigidly connected to the main shaft 5 while the fast and loose pulleys 6 and 7 are carried by the sleeve 16 on the main shaft. The pinion 17 is carried by the sleeve 16 and the pinion 18 is loosely mounted on the shaft 5. A sliding clutch member 19 is splined to and slides on the shaft 5 and by its clutch faces is adapted to engage and lock to the

shaft either the pinion 17 or 18. A gear 20 mounted in the rear of the shaft 5 meshes with the pinion 17 and carries a crank-pin connected by a connecting rod to a segmental gear 22 in mesh with the pinion 18. It will thus be seen that when the sliding clutch member 19 is thrown to the right in engagement with the pinion 17, the bevel gear 150 will be driven continuously and plain circular knitting or ribbed work will result according as to whether the dial needles are out of or in action while if the sliding clutch 19 be thrown to the left into engagement with the pinion 18 the bevel gear 150 will be given an oscillating movement and reciprocating knitting will be performed. The sliding clutch member 19 is shown as operated by a lever 23 fulcrumed at 24 on the frame.

A pattern shaft 25 is mounted in the frame of the machine and has fast thereon a ratchet wheel 26 operated by a pawl 27 carried by the swinging lever 28 pivoted at 29 which lever is held by a spring 30 against the face of the cam 31 mounted upon the shaft 32 which shaft also serves as a pivotal center of the segmental gear 22. Thus at each reciprocation of the segmental gear 22 the pawl 27 is also reciprocated to ratchet around the ratchet wheel 26. But the pawl 27 is normally disengaged from the ratchet wheel by a controlling lever 33 overlying and operated by the main pattern chain 34. This controlling lever is normally held out of engagement with the ratchet wheel by the spring 35. When it is desired that the ratchet wheel 26 shall be moved, a suitably positioned lug on the pattern chain 34 raises the controlling lever 33 against its spring 35 thus dropping the pawl 27 into engagement with the ratchet wheel and a step by step rotation is then given to the pattern shaft 25 for a period determined by the number of links of the pattern chain provided with the required lugs or by the length of time during which any single link having a proper lug is maintained in position to allow the operation of the said pawl.

The shaft 25 has rigidly secured thereto a drum or disk 36 having a section of its periphery provided with ratchet teeth. A pawl 37 co-operates with these teeth at proper times and is pivotally mounted on the upper end of a lever 38 also pivoted on the shaft 29 and held by a spring 39 up against a part oscillating on the shaft 32 with the segmental gear 22 so that this pawl is normally given a continuous oscillating movement.

The riser 15, already described, by which the change from ribbed to plain knitting and vice versa is initiated, is operated by pins or projections carried with the pattern shaft 25 and one of these pins is shown at 40 projecting from the drum or disk 36.

This pin at the proper time comes into contact with a lever 41 fulcrumed at 42 to the frame and connected to the riser and thus the riser is actuated.

5 The pattern shaft 25 also carries integral therewith a clutch controlling disk 43 provided on its periphery with a cam groove 43^a co-operating with a stud 43^b on the lever 23 and which at the required times shifts 23 and which at the required times shifts 10 the lower end of the lever 23 to the left or to the right as required thus causing the sliding clutch member 19 to engage the pinion 17 or the pinion 18 and initiate circular or reciprocating work as required.

15 The main pattern chain 34 is carried by a sprocket wheel 44 which with a connected ratchet wheel 45 is loosely mounted on the shaft 25. This ratchet wheel at the required times is operated by a pawl 46 pivotally connected at 47 to the oscillating segmental gear 22 so that it is continuously in motion. The pawl 46 has a wide face so that it not only engages the ratchet wheel 45 but at times also engages with the projections 48 20 on the periphery of the clutch controlling disk 43. These projections control the engagement and disengagement of the pawl 46 with the ratchet 45.

The mechanism thus far described will, 30 in a manner familiar to those skilled in the art, control the changes to ribbed, plain circular or reciprocating knitting at the required time and the length of knitted web while either kind of knitting is being performed will be measured by the number of 35 courses knitted and determined by the pattern mechanism.

The determination of the actual linear extent of the knitted web during any desired period is secured and the change to another kind of knitting upon the completion of a predetermined actual linear length will be effected by the mechanism now to be described.

45 A friction wheel 49 is freely mounted at the end of a stub shaft 50 secured to some portion of the frame and arranged so that the periphery of the wheel will be close to the path of the knitted web and adjacent 50 the bottom of the cylinder. The periphery of the wheel is given a rough or friction surface and for that purpose may be provided as indicated with some such material as card clothing. A guard 51 shown as a 55 smooth metal plate is mounted on the end of an arm 52 projecting from a hub 53, loosely mounted on the shaft 50 and this guard extends across the periphery of the wheel. A coiled spring 54 secured at one end of 60 the hub 53 and at the other end to a block 55 rotarily adjustable on the shaft 50 acts normally to swing the guard to throw the guard to a position where it will not interfere with the contact of the wheel and the 65 knitted web. An arm 56 rigid with the hub

53 projects in a direction opposite to the arm 52 and is provided with connections by means of which the guard may be thrown downwardly in opposition to the spring 54 to a position between the wheel and the knitted web thus preventing contact of the former with the latter. The movement of the guard 51 in either direction is limited by a pin 501 engaging one of the faces 502 of a slotted collar 503 adjustably secured to the shaft 50 by a set screw 504. Thus by operation of the arm 56 at the required times the friction wheel may be rocked into and out of contact with the knitted web.

The mechanism for controlling the operation of the guard 51 is illustrated in detail in Fig. 3. The cam disk 57 is rigidly secured to the pattern shaft 25 and provided on its end surface with the face cam groove 58. A sprocket wheel 59 is mounted on the shaft 50 to turn therewith in unison with the friction wheel 49 and carries a pattern chain 60 provided at the required intervals with suitable lugs or risers. A bell-crank lever 61 is mounted on a shaft 62 and has one arm 63 extending upwardly and provided with a stud riding in the face cam 58, while its other arm 64 has pivotally connected thereto a link 65 provided at its opposite end with a slot 66. The slotted end 66 of the link 65 engages a stud on the end of the shorter arm 67 of another bell-crank lever 68 fulcrumed at 69 while the longer arm 70 of this bell-crank lever has its free end cam shaped to present two surfaces, one of which 71, is nearer the fulcrum 69 than the other 72 and these cam surfaces co-operate with a pin 73 projecting from the pawl-carrying arm 38. When the surface 71 is in engagement with the pin 73, 10 the pawl 37 may be actuated fully but when the surface 72 is in engagement with the pin 73 the pawl 37 is prevented from having its full movement from its actuating part and cannot, therefore, act to turn the 110 ratchet disk 36. An arm 74 is connected to move with the bell-crank lever 68 on the shaft 69 and has its upper end pivotally connected to a link 75. This link 75 at its opposite end is provided with a slot 90 engaging a pin 91 on the end of the arm 56.

The construction is such that with the parts in the position shown in Fig. 3, that is with the stud on the arm 63 of the bell-crank lever 61 in the high part of the face cam 58, the bell-crank 61 will have been rocked to swing the bell-crank lever 68 upwardly and also to swing the arm 74 rearwardly and to rock the guard 51 downwardly to prevent the friction wheel 49 from contacting with the knitted web. When now, a change in knitting is effected and it is desired that the web shall be measured by the friction wheel 49, the pattern shaft 25 turns to such a position that the 130

stud on the end of the arm 63 rides into the low part of the face cam 58. The bell-crank lever 61 is then rocked forwardly carrying with it the link 65 by reason of the slot 66 at its end without moving the bell-crank lever 68. On the next forward movement of the pawl 37, the bell-crank lever 68 drops and the cam surface 72 comes behind the pin 73 thus holding the pawl 37 in such a position that it cannot actuate its ratchet wheel. The arm 74 swings forwardly with the bell-crank lever 68 and the spring 54 is allowed to act to throw the guard 51 upwardly and establish contact between the friction wheel 49 and the knitted web. At the same time one of the projections 48 on the clutch controlling disk 43 rides beneath the pawl 46 and lifts it out of engagement with the ratchet wheel 45 and the operation of the pattern chain 34 thus ceases. Knitting then continues and is measured by the friction wheel 49.

When a predetermined length of web has been knitted a suitably positioned lug or riser on the pattern chain 60 comes beneath the upper end of the arm 74 rocking the arm 74 and the connected bell-crank lever 68 rearwardly. Owing to the slot in the end of the link 75 this slight rocking movement takes place without changing position of the guard 51 but the arm 70 rises sufficiently to free the pawl 37 and allow it to actuate its ratchet wheel. Up to this time the pawl 46 has been elevated by a projection on the clutch controlling disk 43, and the pattern chain 34 has been left with a lug ready to come beneath the controlling lever 33 to allow the pawl 27 to actuate the ratchet wheel 26. But with the pawl 27 thus out of operation, when the pawl 37 is thus freed to its full movement, it turns the main pattern shaft and rotates it until the pawl 46 drops down off the projection on the clutch controlling disk and engages and drives the main pattern chain ratchet wheel 45, thus immediately setting the pawl 27 into engagement with the ratchet wheel 26. The main pattern shaft 25 is now driven continuously until the high part of the face cam 58 rocks the bell-crank lever 61 rearwardly giving an extended movement to the arm 74 and throwing the guard 51 between the friction wheel 49 and the knitted web. The pawl 27 is then thrown out of operation by the main pattern chain 34 and the measurement of the web then being knit is determined by the number of courses as provided for by the risers or lugs on the main pattern chain 34. The parts are all so timed and positioned that the friction wheel 49 is thrown out of operation a fixed distance before the change from one kind of knitting to another is effected.

When a change of knitting is again effected requiring measurement by the friction

wheel 49, a lug or riser on the main pattern chain 34 throws the pawl 27 again into operation and the main pattern shaft is ratcheted around to bring the stud on the end of the arm 63 into the low part of the face cam 58, and the operation is repeated as described. It will thus be seen that by properly positioning the various lugs, pins and risers, either kind of knitting may be measured by the number of courses or by its actual linear length and a change from one kind of knitting to another effected when a predetermined length of knitted web measured either way has been reached.

Having fully described my invention, what I claim as new and desire to secure by Letters Patent is:—

1. In a knitting machine for knitting different kinds of work, a friction wheel located in the path of the web and adapted to be rotated thereby, a movable guard which, when interposed between the wheel and the web prevents the rotation of the wheel by the web, a pattern chain driven by said wheel and operating to effect the movement of the guard into the interposed position upon the completion of a predetermined length of knitted web and pattern controlled means for effecting the movement of said guard out of interposed position.

2. A knitting machine comprising means for knitting ribbed and plain work and for changing from one to the other, a friction wheel located in the path of the web and adapted to be rotated thereby, means for automatically causing the co-action of said web and wheel upon the commencement of ribbed work and means operated from said wheel and actuated upon the completion of a predetermined length of web to effect a termination of the co-action of said wheel and web and a setting into action of the means for knitting plain work.

3. In a knitting machine, means for knitting ribbed work, plain circular work and reciprocating work and for changing from one to the other, means operated by contact with the knitted web for causing the cessation of either circular or ribbed knitting and the commencement of another of the aforesaid kinds of knitting upon the completion of a predetermined length.

4. A knitting machine comprising means for knitting ribbed work, plain circular work and reciprocating work and for changing from one to the other, means operated by contact with the knitted web for causing the cessation of one kind of knitting and the commencement of another kind of knitting upon the completion of a predetermined length, and means for causing the cessation of one kind of knitting and the commencement of another kind of knitting upon the completion of a predetermined number of courses and pattern controlled means for

throwing either of the last two means into operation.

5. In a knitting machine, a friction wheel located in the path of the web and adapted to be rotated thereby, to measure the length of the knitted web, means for determining the number of courses in the web being knitted and means for automatically causing, when required, the co-action of the said 10 wheel and web, whereby the length of the

web may be measured either by the wheel or by the number of courses knit.

In testimony whereof, I have signed my name to this specification, in the presence of two subscribing witnesses.

EDISON E. RANDALL.
